OVERTHROW MECHANISM

William J. Pearson and Thomas I. Brown, Los Angeles, Calif., assignors, by direct and mesne assignments, to Elizabeth B. Pearson, Los Angeles, Calif.

Application April 9, 1932, Serial No. 604,294

7 Claims. (Cl. 235—131)

One of the objects of our invention is to provide an overthrow mechanism so constructed as to prevent the spinning of the register wheels at the time when the operating means has 5 reached the limit of its travel.

A further object is to provide means for locking said registering wheels when said operating means is moving from normal position and means for releasing said locking mechanism while the 10 operating means is returning to normal position.

Another object of our invention is to provide a convenient means for the normal resetting of the register wheels in a meter unit so that they may be placed in any decided position without 15 the necessity of previously releasing the register locking mechanism.

In the drawings:

Figure 1 is a sectional view through the meter unit.

20 Figure 2 is a sectional view taken on line 2—2 of Figure 1 with one of the register wheels shown in section, the others being in elevation.

Figure 3 is an enlarged elevation of one of the wheels and taken on line 3—3 of Figure 2.

25 Figure 4 is an enlarged elevation of one of the register wheels and taken on line 4—4 of Figure 2.

30 Figure 5 is an enlarged sectional view of a register wheel showing the relation of a spring ratchet dog to the internal and external ratchet notches. This view also makes clear the assembly of the other parts of the register wheel.

Figure 6 is a fragmentary perspective view 35 showing the relation of the various parts of the overthrow mechanism.

The overthrow preventing mechanism disclosed in this invention is included in the meter unit 65. Also included in the meter unit 65 are a descending register 71, and an ascending register 78, which registers are composed of a series of similar indicia wheels 364. For the purposes of this application we will refer to only one of each series. The register wheels are operated by the movement of the sector 447. The point 446 of the sector 447 engages with any suitable positioning means (not shown in this drawing) the position of which is predetermined by means of a controlling apparatus, thus limiting the movement of the sector 447. When the shaft 461 and the cam B, is rotated, the sector 447, supported by the cam roller 445 is permitted to rotate, around the shaft 439, under the influence of the spring 450 until point 446 engages with the aforesaid positioning means. This movement rotates the 55 pinions 373 in a clockwise direction.

The overthrow mechanism consists of a multiple number of latches 7, all of which are similar in construction and operation, the latch stop pin 7', the connecting fork 10, the spring 16, the operating lever 13, and the springs 17. As shown in Figs. 1 and 6, the fork 10 is located on the near side of the latch 7 and the stop pin 7' is provided to insure the positive withdrawal of the latch 7, while at the same time permitting the spring 16 to stretch when the latch is engaged. The fork 10 is provided with a slot 10' adapted to engage the stud 13' on the operating lever 13. The latch 7 engages with the ratchet wheels 18 and 19, which are riveted to the webs 363 of the indicia drums 364 as shown in Figures 4 and 5. Any counter-clockwise motion of these wheels is prohibited while the latch 7 is so engaged, by means of the fingers 20 and 21. Upon the shaft 461 being rotated in a counterclockwise direction, the cam surface 24 which is rigidly fixed to the cam B is revolved until it disengages from the point 25 of the lever 13, permitting said lever to move counterclockwise under the influence of the spring 17.

The disengagement, so effected, is timed to occur after the completion of the downward movement of the point 446, and before the beginning of the upward movement of the said point. Upon the further counter-clockwise rotation of shaft 461 the cam B engages with the cam roller 445 and restores the sector 447 to its normal position. This clock-wise movement of the sector 447 is transmitted to a counter clockwise movement in pinions 373 and through them to the indicia drums 364 by means of the ratchet dogs 375 as will be further explained. The leading edge 26 of the cam 24 is so disposed that it will engage the point 25 of the lever 13 at the moment when the roller 445 and the sector 447 have attained their maximum clock-wise movement. When the lever 13 is forced back by the cam surface 24, the motion is transmitted through the fork 10, the spring 16, and the latch 7, to the fingers 20 and 21, which engage with the ratchet wheels 18 and 19, said ratchet wheels being an integral part of the indicia drums 364 as will be shown. By this means the indicia drums are brought to a definite stop at the moment when the sector 447 ceases to impart motion, and any further movement of the wheels 364 due to momentum or other causes is rendered impossible.

The spring 16 is included in the power transmission means as a safe guard against undue pressure on the fingers 20 and 21 and also to provide a means of manually releasing the latch 55

7 without revolving the shaft 461. This operation is performed as follows—When the door 294 in the cover plate 290 is opened the cam surface 29 is rotated around the shaft 30 so as to engage 5 with the cam surface 31 of the latch 7 and to rotate the said latch in a clock-wise direction around the shaft 391, thus disengaging the latch 7 from the ratchet wheels 18 and 19, and so from the indicia drums 364. This feature is included 10 as a convenience in the manual resetting of the wheels 364 in the descending register 77.

The construction of the register wheel 364 is made plain by referring to Figures 3, 4 and 5, and the relation of the cam surface 24, the operating lever 13, the fork 10, and the latch 7 to the ratchet wheels 18 and 19, is illustrated in Figure 2, which is a partial sectional elevation through line 2—2 of Figure 1. The relation of the sector 447 and cam roller 445 to the cam B is also shown in this 20 figure.

The register wheels 364 include an inner sleeve 356 having a spring disc 357 provided on the inner end thereof, this disc having two spring dogs 358 which are deformed so as to be continually urged 25 in the direction in which one of these is shown in Figure 5. On the opposite end of the sleeve 356 is rigidly mounted a large diameter transfer gear 360 which is shown in Figure 2.

Rotatably mounted on the sleeve 356 is a sleeve 361, which has a flange at its inner end, upon 30 which is secured the web 363 of an indicia drum 364. The indicia drum 364 is adapted to carry digits from one to nine and zero, serially arranged. Also secured to the sleeve 361 is a carry-over disc 366, which in the present embodiment is formed 35 by a pair of discs, the outermost of which is provided with ratchet notches 367, which are adapted to receive the dogs 358 as shown in Figure 5. There are ten of the ratchet notches 367 which 40 are uniformly spaced circumferentially about the axis of the disc 366, as shown in Figure 4. The disc 366 has a recess 368 formed therein and a pair of teeth 369 are provided to extend outwardly from the disc alongside of this recess as shown in 45 Figure 4.

Formed in the inner face of the web 363 of the indicia drum 364 are ten ratchet notches 370 which are similarly arranged to the ratchet notches 367.

50 Rotatably mounted on the sleeve 361 is a third sleeve 372 having a gear 373 at its outer end and carrying a spring dog plate 374 on its inner end, there being a pair of oppositely disposed spring dogs 375 formed from this plate so as to be continually urged into engaging with the ratchet notches 370 as shown in Figure 5.

A series of register wheels 364, are placed close together on the shaft 355 to form the descending register 77 so that the carry-over gear 360 of each 60 of these wheels is disposed adjacent to the carry-over disc 366 of the adjacent register wheel. The teeth 390 of the carry-over gears 402 are disposed in the same radius, and are of the same pitch as the teeth 369 on the carry-over disc 366 and the 65 teeth of the carry-over gears 360.

The ratchet wheels 18 and 19 are rigidly fixed as by rivets 362 between the webs 363 of the indicia drums 364 and the discs 366 as shown in Figure 5. The teeth of the ratchet wheels are so disposed as 70 to engage with the fingers 20 and 21 of the latch 7 at the moment when the fingers are depressed by the influence of the cam surface 24 on the point 25 of the operating arm 13.

Included in the assembly of the wheels 364 are 75 two spacers 32 which will preclude any possibility

of the fingers 20 and 21 binding on either the drum 364 or the disc 366.

While the construction shown and above described is entirely satisfactory for the purpose primarily set forth, the ideas are capable of various embodiments, with suitable modifications and changes, all coming within the scope of the claims which follow.

A more detailed description of the operation is as follows: The rotation of the cam B by means 10 of the shaft 461, to which it is rigidly fixed, permits the counterclockwise movement of the sector 447 when the surface B' of the cam B is removed from the path of the roller 445. This movement of the sector 447 is imparted to each of two pinions 15 373, which together, with their respective spring ratchet dogs 375, are impelled in a clockwise direction.

The pinions 373 are mounted within the register wheel assembly 77, and are so constructed as to 20 turn in this direction without influencing the position of the indicia drum 364, the Geneva tooth 369 or the carry-over pinion 390. The indicia drum is held against clockwise movement by the external spring ratchet dog 358, to which it is rigidly 25 affixed, and the aforesaid pinion 390.

The movement of the sector 447, if unchecked would continue until the roller 445 came to rest on the low point of the cam B and this movement is designed to be equal to exactly nine teeth on 30 the sector 447 and the pinion 373 which in turn will equal nine ratchet teeth 370 in the indicia drum 364. However, the counterclockwise movement of the sector 447 may be arrested at any one of nine equal spaces, each corresponding to 35 one ratchet tooth 370, by the introduction of any suitable stop such as a step of a step-cam under the point 446 of the sector 447.

At this point in the rotation of the cam shaft 461, the point 25 of the arm 13 disengages from 40 the surface 24 of the cam 26 and the arm moves in a counterclockwise direction under tension of the spring 17. This motion is transmitted through the stud 13', the slot 10' of the fork 10, and the stud 1' to the latch 7, which moves in a 45 clockwise direction a distance sufficient to disengage the hooks 20 and 21 from the teeth of the ratchet discs 18 and 19 which discs are rigidly affixed to their respective indicia drums 364.

Upon further movement of the cam shaft 461 50 the leading edge of the cam B engages the roller 445 of the sector 447 and impells said sector in a clockwise direction. This movement is transmitted to the pinions 373 in each of the two register wheels, and so to the ratchet dogs 375. The 55 counterclockwise movement of the said ratchet dogs 375 is imparted to the indicia drum 364 by means of the ratchet teeth 370 with which the dogs engage.

It is obvious then, that the amount of clockwise 60 movement of the sector 447 is determined by the counterclockwise movement previously imparted by the spring 450 and limited by the position of a stop placed under the point 446, so that when the roller 445 of the sector 447 is fully restored to 65 the high point of the cam B, the pinions 373 will have turned a number of teeth corresponding to the position of said stop under point 446.

Furthermore, this counterclockwise movement 70 of the pinions 373 will turn the indicia drum 364 a corresponding distance and a new figure will appear in the window 294. However, the momentum imparted to the indicia drum 364 might cause said drum to continue its motion after its driving ratchet dog 375 had come to rest, so at the precise 75

moment that the roller 445 arrives at the highest point on the cam B, the leading edge of the cam 26 engages the point 25 of the arm 13.

The clockwise movement so imparted to the arm 13 is transmitted through the stud 13', the slot 10' of the fork 10, and the spring 16 to the latch 7. The hooks 20 and 21 of the latch 7 engage simultaneously with each of the two register wheels and the said engagement is so timed as to occur when the driving dogs 375 reach the limit of their counter-clockwise motion. This completes one cycle of the mechanism.

I claim:

1. In an overthrow preventing mechanism, latching means, an operating lever, said means comprising a latch, and a fork, said fork connecting said latch and said lever said latch and said fork being constrained to act simultaneously by a spring.
2. In combination with a meter unit, two register wheels and means for simultaneously locking said register wheels, said means comprising a latch common to said register wheels and operating means for said latch, said operating means consisting of a positively driven cam and a lever connecting said latch and said operating means.
3. In combination with a meter unit, two register wheels and means for simultaneously locking said register wheels, said means comprising a latch common to said register wheels and operating means for said latch, timing means so arranged as to prevent movement of said register wheels beyond the points to which they are positively driven.
4. In combination with a meter unit, a gear sector plate in said unit, two register wheels and

means for simultaneously locking said register wheels, said means comprising a latch common to said register wheels and operating means for said latch, timing means comprising a cam and a latch operating arm, said arm arranged to operate in conjunction with a register operating sector plate.

5. In combination with a meter unit, two register wheels, means for simultaneously locking said register wheels, gear sector plates in said meter for actuating said register wheels, means for causing said sector plates to move from normal position and means for causing said locking means to remain engaged with said register wheels during said movement of said sector plates.

6. In combination with a meter unit, two register wheels, means for simultaneously locking said register wheels, gear sector plates in said meter for actuating said register wheels, means for causing said sector plates to move from normal position and means for causing said locking means to remain engaged with said register wheels during said movement of said sector plates, and means for releasing said locking means while said gear sector plates are being restored to their normal position.

7. In an overthrow preventing mechanism, latching means comprising a mechanically operated device, said device comprising a latch, a connecting fork, a spring controlling said connecting fork, an operating lever and a cam, said latch and said operating lever connected together by said connecting fork said latch being constrained by said connecting means to engage simultaneously with two register wheels.

WILLIAM J. PEARSON. 35
THOMAS I. BROWN.
